MINING MACHINE

Frank A. Lindgren, Western Springs, Ill., assignor to Goodman Manufacturing Company, Chicago, Ill., a corporation of Illinois

Application November 18, 1933, Serial No. 698,599

6 Claims. (Cl. 262—28)

This invention relates to improvements in mining machines and more particularly to mining machines of the track mounted type adapted, in particular, to cut arcuate kerfs in entries or narrow rooms above the level of the mine bottom, and has among other objects to provide a new and improved mining machine of the class described constructed with a view towards compactness and efficiency of design, utmost efficiency and simplicity of operation, particularly arranged for traveling and cutting where the track gauge is narrow, where the radius of the curves of the tracks is relatively short, and where the coal seams are of a relatively steep pitch.

My invention may be more clearly understood with reference to the accompanying drawings in which:

Figure 1 is a top plan view of one embodiment of my invention with parts broken away and in section to more clearly show the details thereof;

Figure 2 is a side elevation of the device shown in Figure 1, with the cutting mechanism shown in substantially longitudinal section;

Figure 3 is an enlarged partial fragmentary plan view of the rearward portion of the device shown in Figure 1, with parts broken away and in section to more clearly show the details of the feed mechanism;

Figure 4 is an enlarged side elevation of the device shown in Figure 1, with parts broken away and in section to show certain details of the feed mechanism, not shown in Figure 3;

Figure 5 is a transverse sectional view of the rearward portion of the device shown in Figure 1, showing certain details of the feed and truck driving mechanism, not shown in Figures 3 and 4;

Figure 6 is an enlarged detail view showing the details of the means for controlling the operation of one of the feed drums; and

Figure 7 is a diagrammatic view showing the method employed for controlling the movement of the machine along a relatively steep grade. Like reference characters refer to like parts throughout the various figures.

Referring now in particular to the drawings and one embodiment of my invention, a truck 10 is provided which is mounted on track wheels 11, 11 and axles 12, 12. The truck 10 is so arranged that its wheel base is relatively short for the negotiation of sharp turns and is also so arranged that it may be readily adapted for narrow track gauges.

A cutting element 13 is mounted on the truck 10 and projects forwardly and rearwardly there-

from and includes a longitudinally disposed motor 14, a cutter frame section 16 disposed forwardly of and secured to the forward end of said motor and a feeding section 17 disposed rearwardly of and secured to the rearward end of said motor.

The cutter frame section 16 provides a pivotal support for a cutter bar 18, having a cutter chain 19 movable thereabout. The cutter bar 18 is mounted on a cutter bar supporting member 20, which cutter bar supporting member in turn is pivotally mounted in the cutter frame section 16 for pivotal movement with respect thereto about a vertical axis in a manner which will not herein be described in detail since it is no portion of my present invention.

A pinion 21 is secured to the forward end of the shaft for the motor 14 and meshes with and drives a spur gear 22 on the rearward end of a shaft 23. A bevel pinion 24 is freely mounted on the forward end of the shaft 23 and is selectively connectible therewith by means of a clutch member 25 in a usual manner. The bevel pinion 24 meshes with and drives a bevel gear 27 secured to the upper end of a vertical shaft 28 which shaft is journaled in the cutter frame section 16 by means of ball bearings in a usual manner. A sprocket 29 is keyed to the lower end of the vertical shaft 28 and meshes with and drives the cutter chain 19 in a closed orbital path about the cutter bar 18.

Referring now in particular to the details of the feeding section 17 and the means for swinging the cutter bar 18 about the axis of the sprocket 29 and feeding said cutter bar in an arcuate path across the coal face, a pair of feed drums 30, 30, herein shown as being coaxially arranged, are provided. The feed drums 30, 30 are arranged adjacent opposite sides of the feeding section 17 and motor 14 and are journaled on eccentric members 31, 31. The members 31, 31 in turn are journaled eccentrically of their centers on sleeves 32, 32, which sleeves in turn are freely mounted on transversely extending shafts 33, 33.

A flange 35 extends inwardly from each feed drum 30 and has an internal gear 36, keyed to the inner periphery thereof. A brake band 37 is adapted to engage the outer periphery of the flange 35 for holding the feed drum 30 from rotation when desired.

Pinions 39, 39 on the outer ends of coaxially arranged horizontal shafts 40, 40 are adapted to mesh with and drive the internal gears 36, 36. The pinions 39, 39 are engaged with or disen-

gaged from the internal gears 36, 36 by means of the eccentric members 31, 31. A member 41 having arms 42 extending outwardly therefrom is secured to the outer end of each shaft 33. The 5 arms 42 of each member 41 are adapted to engage suitable grooves formed in the outer face of each member 31 so that rotation of either of the shafts 33 will cause pivotal movement of the respective eccentric member 31 for shifting the internal gear 10 36 into engagement with or disengagement from the respective pinion 39. An operating lever 43 is keyed to the inner end of each shaft 33 for pivotally moving said shafts and moving the drums 30 about axes eccentric of their center for 15 selectively connecting the feed drums 30, 30 with the motor 14. The operating levers 43, 43 may be locked to hold the internal gears 36, 36 in mesh with or disengagement from the pinions 39, 39 by means of any suitable arrangement (not 20 shown).

Suitable flexible feeding members, such as flexible cables 44, 44 are adapted to be wound on the feed drums 30, 30 and their free ends are adapted to be connectible with a connecting member 45 secured to and extending upwardly from the cutter bar support member 29 (see Figure 1). It is thus apparent that when one feed drum 30 or the other is driven by power from the motor 14, that the cutter bar 18 may be pivotally 25 moved in one direction or another for feeding the cutter bar 18 in an arcuate path across the front of the truck 10. Either of the feed drums 30, 30 may be power driven at the same time in a manner which will hereinafter more fully appear, or one 30 of said feed drums may be power driven while the other drum may be retarded by means of the brake band 37 under control of the operator.

Referring now in particular to the means for independently driving the feed drums 30, 30 from the motor 14, an armature pinion 47 is keyed on the rearward end of the shaft for the motor 14. The armature pinion 47 meshes with and drives a spur gear 48 secured to the forward end of a longitudinally extending shaft 49. The longitudinally extending shaft 49 is journaled in a bearing support member 50 on suitable ball bearings, which bearing support member 50 is in turn detachably secured to the frame for the feeding section 17.

50. A worm 51 is formed integral with the longitudinally extending shaft 49 intermediate its supporting bearings in the bearing support member 50 and meshes with and drives a worm gear 53 secured to a sleeve 54. The sleeve 54 is journaled 55 on its outer periphery in suitable ball bearings held in the lower portion of the feeding section 17 in suitable bearing supports in a usual manner and has spur gears 55, 55 formed integral with its outer ends. The spur gears 55, 55 form driving members or sun gears for planetary geared reduction devices 56, 56 arranged coaxially with the 60 shafts 40, 40 for driving said shafts and the pinions 39, 39 at either high or low frictionally controlled speeds independently of each other.

65. Inasmuch as the construction of the two planetary gear reduction devices 56, 56 is similar, the construction of one only will herein be described in detail. The spur gear 55 meshes with and drives planetary pinions 57, 57 freely mounted on shafts 58, 58 secured adjacent their ends in a cage 59. Planetary pinions 62, 62 are formed integral with the planetary pinions 57, 57 and are disposed to one side thereof and mesh with 70 75 and drive an internal gear 60 carried on a spider

61, which spider in turn is keyed to the shaft 40 for driving said shaft.

The cage 59 is provided with a flange 63, which extends outwardly from its inner side and which is adapted to be engaged by a friction band 64 for holding said cage from rotation or permitting said cage to rotate under the control of said friction band. An internal gear 65 is journaled on the inner periphery of the flange 63 of the cage 59 for rotation with respect thereto and meshes with the planetary pinions 57, 57. A flange 66 is formed integral with the internal gear 65 and is disposed adjacent the flange 63 of the cage 59 and its inner periphery encases the outer periphery of the internal gear 60. A friction band 67 surrounds and engages the flange 66 for holding the internal gear 65 from rotation or permitting said internal gear to rotate under the control of friction.

The friction bands 64 and 67 are controlled by 20 means of a hand wheel 68 disposed adjacent the rearward end of the feeding section 17 and keyed on the rearward end of a shaft 69 journaled in the feeding section 17, and extending angularly upwardly from said hand wheel. An operating 25 member 70 is threaded on the shaft 69 for translational movement with respect to the hand wheel 68 upon rotation of said hand wheel. The operating member 70 is provided with oppositely extending lugs 71 and 72. The lug 71 is adapted to engage a lug 73 extending upwardly from one end of the friction band 64, while the lug 72 is adapted to engage a lug 74 extending upwardly from one end of the friction band 67. Lugs 75 and 76 extend upwardly from the opposite ends of the friction bands 64 and 67 respectively, and are adapted to respectively engage suitable stops formed integral with and extending downwardly from the top cover of the feeding section 17.

It should be noted with reference to Figures 3 40 and 6 that the lugs 71 and 72 extend outwardly in opposite directions from opposite ends of the member 70 so that when the hand wheel 68 is rotated in one direction, the friction band 64 may be engaged with the flange 63 for holding 45 the cage 59 from rotation while the friction band 67 is permitted to be disengaged from the flange 66 formed integral with the internal gear 65, and when rotated in an opposite direction the internal gear 65 may be held from rotation permitting 50 the cage 59 to be free to rotate.

When the cage 59 is held from rotation by the friction band 64, the internal gear 60 will be driven through the sun gear 55, planetary pinions 57 and planetary pinions 62, which will rotate the 55 shaft 40 at a relatively high rate of speed. When the internal gear 65 is held from rotation by the friction band 67 and the cage 59 is free to rotate, the internal gear 60 will be driven through the spur gear 55 and planetary pinions 57 and 62, 60 moving in an orbital path about the internal gear 65, at a relatively slow rate of speed. It may thus be seen that each of the feed drums 30, 30 may be selectively driven from the motor 14 at either a high or low frictionally controlled speed, 65 controlled by the hand wheels 68, 68. During normal operation it is only necessary to turn the hand wheels 68, 68 in one direction or another to control the speed of rotation of the feed drums 30, 30. When desired, however, the feed drums 70 30, 30 may be disengaged from the drive pinions 39, 39 by means of the operating levers 43, 43 to permit said feed drums to freely rotate independently of the planetary gear reduction devices 56, 56. While the planetary gear reduction devices 75

56, 56 may be used as a means of retarding rotation of the feed drums 30, 30, when using either of said feed drums as a retarding device, it is preferable to use the brake bands 37 to retard rotation of the desired feed drum, said feed drum being disconnected from the respective planetary geared reduction device 56, when being so retarded by means of the respective operating lever in order to relieve all internal strains from said 10 planetary gear reduction devices.

With reference now in particular to the truck drive and the auxiliary means for propelling the truck when moving or cutting along a pitching seam, a winding drum 79 is journaled on a shaft 15 80 supported at its ends in a portion 81 depending from the rearward portion of the feeding section 17. A spur gear 83 is secured to one of the flanges of the winding drum 79 and is meshed with a spur pinion 84 freely mounted 20 on a transversely extending shaft 85 journaled at its ends in the depending portion 81 of the feeding section 17. A hub 86 of the spur pinion 84 is journaled in the depending portion 81 and has clutch jaws 87, 87 extending from its outer 25 end, adapted to be engaged by clutch jaws 88 formed integral with a clutch member 89 feathered on the transversely extending shaft 85 for selectively driving said spur pinion and the winding drum 79 from said shaft. The transversely 30 extending shaft 85 in turn is driven from the shaft 40 on the left hand side of the machine, when looking towards the cutter bar 18, by means of a spur gear 90 keyed on said shaft, an idler gear 91 driven therefrom and a spur gear 92 35 meshing with said idler gear and keyed on said transversely extending shaft. Thus the winding drum 79 may be driven from one planetary gear reduction device 56 at either a high or low frictionally controlled speed simultaneously or independently of rotation of the feed drums 30, 30.

A sprocket 93 is freely mounted on the right hand outer end of the transversely extending shaft 85. The sprocket 93 is journaled on its hub in the depending portion 81 and its inner 40 end has clutch jaws 94 formed integral therewith, which are adapted to be engaged by clutch jaws 95 formed integral with a clutch member 96 feathered on the transversely extending shaft 85 for selectively driving said sprocket from said shaft. The sprocket 93 is operatively connected with the rearward truck wheels by means 45 of a chain and sprocket drive generally indicated by reference character 97, while the forward and rearward truck wheels are connected together by means of a chain and sprocket drive, generally indicated by reference character 98. The truck may thus be driven at either a high or low frictionally controlled speed independently of rotation of the winding drum 79 50 and independently of rotation of the feed drums 30, 30.

The winding drum 79 is adapted to have a flexible feeding member such as a flexible cable 99 secured thereto at one of its ends. The flexible cable 99 may extend rearwardly from the winding drum 79 for moving the mining machine in a rearward direction along a mine track, but usually extends forwardly of the mining machine beneath the cutting element 13, through the truck to a fixed abutment remote from the machine proper for moving the machine along the track at either a high or low frictionally controlled speed. As herein shown the flexible cable 99 extends forwardly from the winding drum 79 over a roller 100 through the frame

for the truck 10 above the truck axles 12 through guide sheaves 101, 101 to a jack 102 interposed between the mine roof and mine floor for moving the mining machine along a track up an incline, or for permitting the mining machine to be lowered down an incline under control of said winding drum, the speed of rotation of said winding drum being controlled by the planetary gear reduction device 56.

During the cutting operation the mining machine is usually held in a stationary position with respect to the track by means of suitable jacks interposed between the machine and the mine roof or mine bottom, the kerf being cut entirely by arcuate movement of the cutter bar 18. In cases where the entries are relatively narrow the cutter bar may be sumped into the coal by movement of the truck along a track actuated either by the winding drum 79, or both the track wheels and said winding drum. After 20 the cutter bar has been sumped into the coal, the machine is held at a stationary position with respect to the track by means of suitable jacks and the kerf is completed in the usual manner.

It may now be seen that a new and improved mining machine of the track mounted type has been provided which is so constructed as to be of a compact form and yet be efficient and flexible in operation; that a new and improved means is provided for independently driving the feed drums which means also serves to effect independent operation of a third drum and the wheels for supporting the truck, which drum and wheels are driven at a speed similar to the speed of rotation of the feeding drums, and that the device of my invention is so arranged that it is particularly adapted for use in mines having pitching seams and relatively steep grades.

While I have herein shown and described one form in which the device of my invention may be embodied, I wish it to be understood that I do not desire to be limited to the precise details or form of construction shown herein, excepting as it may be limited in the appended claims.

I claim as my invention:

1. In a track-mounted mining machine, a truck mounted on wheels and axles, a motor, a cutter bar projecting forwardly of said truck and mounted for pivotal movement about a vertical axis disposed forwardly of said truck, means driven by said motor for driving said truck including a planetary geared reduction device, a shaft driven thereby and a selective connection between said shaft and truck wheels, and feeding mechanism therefor comprising a pair of feed drums disposed rearwardly of and at opposite sides of said motor and a third feed drum disposed rearwardly of said first-mentioned feed drums and selectively driven from said shaft.

2. In a track-mounted mining machine, a truck mounted on wheels and axles, a motor, a cutter bar projecting forwardly of said truck and mounted for pivotal movement about a vertical axis disposed forwardly of said truck, means driven by said motor for driving said truck including a transversely arranged shaft driven from said motor at either a high or low speed and a selective connection between said shaft and truck wheels, and feeding mechanism therefor comprising a pair of coaxially arranged feed drums disposed rearwardly of and at opposite sides of said motor, and a third drum disposed rearwardly of and between said first-mentioned drums and selectively driven from said shaft independently of said truck driving mechanism.

3. In a track-mounted mining machine, a truck mounted on wheels and axles, a motor, a cutter bar projecting forwardly of said truck and mounted for pivotal movement about a vertical axis disposed forwardly of said truck, means driven by said motor for driving said truck including a shaft driven by the rearward end of said motor and arranged for rotation about a transverse axis, a shaft parallel thereto and driven thereby and a selective connection between said last-named shaft and truck wheels, and feeding mechanism therefor including a pair of coaxially arranged feed drums disposed rearwardly of and at opposite sides of said motor, each of said feed drums having a flexible feeding member having operative connection with said cutter bar for swinging said cutter bar in opposite directions without reversal of said motor, and a third winding drum disposed rearwardly of and between said first-mentioned drums and selectively driven from said last-named shaft independently of said truck driving mechanism for moving said machine along the track at a high or low speed independently of or in cooperation with said truck driving mechanism.
4. In a track-mounted mining machine, a truck mounted on wheels and axles, a motor, a cutter bar projecting forwardly of said truck and mounted for pivotal movement about a vertical axis disposed forwardly of said truck, means driven by said motor for driving said truck including a planetary geared reduction device, a shaft driven thereby and a selective connection between said shaft and truck wheels, feeding mechanism therefor comprising a pair of feed drums disposed rearwardly of and at opposite sides of said motor and a third feed drum disposed rearwardly of and beneath the axis of rotation of said first-mentioned feed drums, and means for driving said feed drums from the rearward end of said motor comprising a planetary geared reduction device coaxial with said first-mentioned planetary, a selective connection from said planetary to one of said feed drums, a selective connection from said first-mentioned planetary to said other feed drum, and a selective connection from said shaft to said third feed drum.
5. In an apparatus of the class described, a track-mounted truck, a mining machine thereon including a motor, a cutter bar disposed forwardly
- thereof and movable about a vertical axis disposed forwardly of said truck, feeding mechanism disposed rearwardly of said motor including a pair of feed drums disposed on opposite sides of said motor for rotation about transverse axes and a flexible feeding member extending from each of said drums to said cutter bar, an independent drive connection from said motor to said winding drums including a worm gear driven by said motor, a planetary geared reduction device arranged on each side thereof and driven thereby, selective drive connections from said planetaries to said drums including a pair of coaxially arranged transverse shafts, a third winding drum rotatable about a transverse axis disposed rearwardly of the axis of rotation of said shafts, truck driving mechanism, and means for selectively driving said third drum and truck driving mechanism from one of said shafts including a parallel shaft driven by one of said coaxial shafts, a selective connection from said parallel shaft to said winding drum and another selective connection from said parallel shaft to said truck driving mechanism.
6. In a track mounted mining machine, a truck mounted on wheels and axles, a motor, a pivoted cutter bar projecting forwardly of said truck, a pair of feed drums disposed rearwardly of said motor adjacent opposite sides thereof for rotation about coaxial transverse axes, means driven from said motor for independently driving said feed drums including a pair of independently operable coaxial planetary gear reduction devices, said planetary gear reduction devices being arranged for rotation about a horizontal axis extending transversely of said motor and each of said planetary gear reduction devices having drive connection with one of said feed drums, a third winding drum for driving said truck along the mine track, disposed rearwardly of said feed drums for rotation about an axis disposed parallel to the axis of rotation of said feed drums, a shaft disposed beneath said feed drums and being driven from one of said planetary geared reduction devices, a selective drive connection from said shaft to said third winding drum, and another selective drive connection from said shaft to said truck wheels.

FRANK A. LINDGREN. 50
